BRUSH FOR CLEANING HAIR CLIPPERS OR THE LIKE

Wayne J. Siekkinen, Hibbing, Minn.

Application October 14, 1958, Serial No. 52,974

Term of patent 7 years

(Cl. D9—2)

Figure 1 is a perspective view of a brush for cleaning hair clippers or the like embodying my new design.

The side not shown is substantially like the side shown in Figs. 1 and 2.

The design for the brush disclosed is characterized by the oppositely disposed abutments or anchor members at the rear having the configuration shown.

I claim:

The ornamental design for a brush for cleaning hair clippers or the like, as shown and described.
